UNITED STATES PATENT OFFICE.

AUGUST R. SCHOENKY, OF SOMERVILLE, MASSACHUSETTS, ASSIGNOR TO THE REECE SHOE MACHINERY COMPANY, OF BOSTON, MASSACHUSETTS, A CORPORATION OF MAINE.

SEWING-MACHINE.

1,171,466.

Specification of Letters Patent. Patented Feb. 15, 1916.

Original application filed September 25, 1912, Serial No. 722,300. Divided and this application filed May 31, 1913. Serial No. 771,000.

To all whom it may concern:

Be it known that I, AUGUST R. SCHOENKY, a citizen of the United States, residing at Somerville, in the county of Middlesex and 5 State of Massachusetts, have invented certain new and useful Improvements in Sewing-Machines, of which the following is a specification, reference being had therein to the accompanying drawings.

10 This invention relates to sewing machines, and for convenience the same is illustrated in connection with the class of machines used in the manufacture of shoes by the welt system, whereby the outsole and welt are sewed together. Other examples of that 15 type of machine which may be referred to for the purpose of supplying details that are omitted herefrom, are illustrated in my prior Patent No. 1,071,355, dated August 26, 1913, 20 and application No. 722,300, filed September 25, 1912, of which last mentioned application this present application is a division.

An object of the present invention is to generally improve the construction and operation of sewing machines of all classes, 25 such for example, as the sole sewing machines of the type referred to.

Another object hereof is to improve the presser foot mechanism so as to permit the lifting of the presser foot at will, by means 30 of a lever or treadle in a more efficient and convenient manner, less injurious to the mechanism than heretofore.

Other objects and advantages pertaining 35 to the present invention will appear in the hereinafter following description, or will be apparent to those skilled in the art.

To the attainment of such objects and advantages, the present invention consists in 40 the novel combinations, arrangements, devices and parts set forth, described and illustrated in the following description and accompanying drawings.

I will first describe one form of machine 45 embodying my improvements and will thereafter point out the novel features in the claims.

In the accompanying drawings forming a part hereof, Figure 1 is a right-hand elevation of certain details, including the presser-foot lifting mechanism, taken in section on the plane 4—4 of Fig. 1, of application 50 722,300, the parts being shown in initial position. Fig. 2 is a view similar to Fig. 1, but

in a position with the presser-foot treadle or lever partly depressed. Fig. 3 is a similar view, with the parts in a position with the treadle fully depressed. Fig. 4 is a similar view showing the parts in position for the automatic release of the work beneath the presser-foot, which occurs during the formation of each stitch. Figs. 5, 6, 7 and 8 represent details of certain parts shown in Figs. 1 to 4.

Similar reference numerals designate corresponding parts in the several figures of the drawings.

I will refer now by reference numerals to the machine parts illustrated in the accompanying drawings.

Extending upwardly from any convenient base is the post 1, supporting at its upper end the head, or casting, 2, which will be of a complicated structure unnecessary to describe, it affording support for various of the working or non-working machine parts hereinafter to be referred to. The main shaft 3 runs in the upper part of the machine, extending from left to right, and supported in bearings or brackets. At the left 75 end of the shaft 3, is a pulley, which may be engaged by a belt for driving the machine. The main shaft may carry a number of cam disks including cam disk 7 shown in the figures. This cam disk at its right-hand 80 side contains a cam 36 for automatically operating the presser-foot during each stitch, imposing upon it an additional pressure, and periodically releasing it during feeding.

The manner of feeding, the manipulation 85 of the thread, the various operating connections and other parts of the machine may be substantially as in said prior applications.

I will now describe the operative connections whereby the cam or groove 36 in the 90 cam disk 7 effects the automatic operation of the presser-foot 23. Particular reference is made to Figs. 1 and 4. The presser-foot 23 is carried at the forward end of presser-foot arm 66, capable of swinging about a 95 fixed stud 67, and having a rear extension or arm 68 rigid with arm 66. There is also a second rear arm or extension 69, which is not rigid, but is spring connected with arm 68 by a spring connection, 70. Extending 100 downwardly from arm 68 is a link 71, connected at its lower end to arm 72, secured on the short longitudinal shaft 73, having a pin 105

74 projecting therefrom, to which is secured
5 spring 75, pulling upon the pin so as to normally keep the presser-foot upon the work with a moderate pressure. This moderate normal pressure is always in effect, unless varied by the automatic mechanism to be described, or by the treadle operated mechanism to be described.

10 The automatic operation of the presser-foot may be effected through a toothed rack 76, on the spring extension or arm 69, a dog 77 engaging said rack, a toothed rack 78 on the arm 68, and a triple dog 79 engaging the rack 78. There is shown a spring 80, pressing dog 77 to rack 76, and a triple spring 81, pressing the components of the triple dog 79 into contact with rack 78.

20 The presser-foot operating lever 82, pivoted at the rear, as shown, possesses a stud 83, which engages the cam groove 36. The forward end of the operating arm 82 has the dog 77, already referred to, pivoted upon it, and carries the spring 80 therefor. The arm 82 also has a projection or heel, 84, shaped and located at proper times to kick and thereby disengage the triple dog 79. This operation occurs when the operating arm 82 descends, and at such time the dog 77 is also disengaged from its rack through 30 a fixed pin 85, located to contact and throw open the dog 77.

35 The operation of the mechanism thus described may be as follows: During the formation of each stitch the work must be released for a sufficient time to permit its feeding, and when the feeding is completed the work is to be again clamped and firmly held under heavy pressure during the various operations of the needle and awl. In 40 Fig. 1, the cam groove 36 is seen to have long and short concentric portions. When the short concentric portion comes into play, the arm 82 is forced downwardly, disengaging the dogs and releasing the presser-foot from excessive pressure, it being then subject only to the moderate pressure of spring 75. When the stud, 83, passes out of the short concentric portion, it is lifted, with the result that the dog, 77, engages the rack, 45 76, to elevate the spring arm, 69, and thereby imposes the force of the powerful spring 70, upon the presser-foot, while at the same time, the triple dog, 79, having a fixed pivot is thrown into engagement with the rack 50 78, thereby positively locking the presser-foot in its depressed position.

55 In order to enable the presser-foot to be lifted at any desired stage of operation, I have provided the following improved mechanism: The vertical rod, 86, will be adapted at its lower end to be depressed by a lever or treadle at the will of the operator. The enlargement at the top of the treadle rod may be termed a head, 87, this being provided with a projection 88, Figs. 4, 5

and 6, adapted when the treadle is lowered to contact the arm 72 and depress it, thus raising the presser-foot. Manifestly, the presser-foot cannot be raised while under heavy pressure without first disengaging the dogs. Loose on the short shaft 73, is a toothed plate, 89. This coöperates with the treadle rod by its pivot connection therewith as shown, so that the plate, 89, guides or directs the treadle rod in its up-and-down movements, while the treadle rod effects oscillations of the plate 89. Coöperative with the toothed plate, 89, is a second toothed plate, 90, the latter being loose upon the stud shaft of the triple dog. Each of the plates 89, 90, is shown as having two teeth, capable of mutually engaging. The triple dog, 79, is provided with a pin 91, for opening it, this pin being for convenience secured to the middle member and adapted to contact the other two members of the dog, as shown in Figs. 7 and 8, the pin, 91, also projecting leftwise beyond the dog, as seen in Fig. 8, so as to stand in the path of the toothed plate 90. The plate 90 has an upwardly extending portion which is centrally notched to accommodate the fixed pin 85. The portion of the plate below the notch is adapted to strike the pin 91 (see Figs. 10 and 11) for disengaging 95 the triple dog 79. The upper portion 92 of the extension plate 90 is adapted to strike a pin 93 for effecting the opening of the dog 77.

100 The operation of the mechanism thus described may be as follows: It will be noticed that the projection 88 on the treadle rod head is normally spaced considerably above the arm 72, so as not to come in contact with the latter for actuating it to raise the presser-foot until the dogs have been released. As is clear in Fig. 5, the depression of the treadle rod first effects a swinging of the toothed plate 89, which, being engaged with the toothed plate 90, swings the latter in a right-hand direction, or toward the rear of the machine. By this action, the plate 90 immediately strikes the pin 91, and also the pin 93, thereby disengaging both of the dogs 77 and 79. The continued depression of the treadle rod brings projection 88 into contact with arm 72, thereby pulling down the link 71 and raising the presser-foot. As will be seen in Fig. 5, the toothed plates 89 and 90 are so shaped that the teeth will disengage after a brief movement, whereby further depression of the treadle will not further actuate the plate 90. The plate 90 therefore serves to disengage the dogs and then comes to rest. This is of very great advantage, for the reason that if the movement of disengagement should be continued throughout the entire depression of the treadle rod, an excessive and unnecessary displacement and 110 115 120 125 130

strain upon the dogs and their springs would be caused. With the mechanism shown, the dogs are only actuated sufficiently to disengage them, and the concentric arc-shaped portion of the plate 89 thereupon during the further depression of the treadle, locks the plate 90 in dog-disengaging position. The subsequent raising of the treadle rod causes first a mere swinging of plate 89, followed by an engagement of its teeth with the teeth of plate 90, thereby restoring both plates to the normal position shown in Figs. 4 and 5.

It will thus be seen that there has been described a presser-foot mechanism embodying the principles and attaining the objects and advantages hereinbefore stated, and other advantages will be apparent to those skilled in the art. Since many features of design and detail may be variously modified without affecting the operation of other features, no restriction to features or details or matters of design is intended excepting as set forth in the claims appended hereto.

25 What is claimed is:

1. In a sewing machine the combination of a work support, a movable presser-foot adapted to bear upon the work upon the support, a dog and rack mechanism for intermittently locking the foot under heavy pressure upon the work, a dog disengager adapted to be positively moved into a position for disengaging the dog from the rack and to be locked in such position, and a shiftable part or treadle having connections whereby the movement of the treadle acts first to move the disengager to a position to disengage the dog, and then to lock such disengager in such position, and then to lift the foot while the disengager remains stationary.

2. In a sewing machine the combination of a work support, a movable presser-foot adapted to bear upon the work upon the support, a dog and rack mechanism for intermittently locking the foot under heavy pressure upon the work, a dog disengager adapted to be positively moved into a position for disengaging the dog from the rack and to be locked in such position, and a shiftable part or treadle having connections whereby the operative movement of the treadle acts first to move the disengager to a position to disengage the dog, and then to lock such disengager in such position, and then to lift the foot while the disengager remains stationary, while the return movement of the treadle restores the presser-foot before restoring the disengager to reengage the dog and rack.

3. In a sewing machine the combination

of a work support, a movable presser-foot adapted to bear upon the work upon the support, a dog and rack mechanism for intermittently locking the foot under heavy pressure upon the work, a dog disengager such as the plate 90 fitted for swinging movement only and adapted to be positively swung toward the dog into a position for disengaging the dog from the rack and to be locked in such position, and a shiftable part or treadle having connections whereby the movement of the treadle operates first to swing the disengager to a position to disengage the dog, and then to lock such disengager in such position, and then to lift the foot while the disengager remains stationary.

4. In a sewing machine the combination of a movable work-engaging member, a locking device therefor, a movable disengager adapted to swing for unlocking said device, and a shiftable part or treadle having connections acting in its operative movement for first moving said disengager to a position to unlock said device, then locking said disengager stationarily in such position, and thereafter during the further movement of said part or treadle retracting said work engaging member from the work while the disengager is locked in position to hold said device unlocked; the reverse movement of said part or treadle acting to first restore the work engaging member before restoring the disengager to permit the relocking of said device.

5. In a sewing machine the combination of a presser-foot adapted to be lifted and lowered and during stitching to be locked under pressure and unlocked, a swinging presser-foot lever, a locking device coöperating with said lever for intermittently locking the presser-foot, a disengager adapted to be moved to a position to unlock said device and to be itself locked in such position, a controlling part or shiftable treadle normally unconnected with said lever so as not to partake of its stitching movements, connections actuatable from said treadle during the first part of the treadle's shifting for moving said disengager to unlock said device and for locking said disengager in such position, and other connections actuatable by the continued treadle shifting movement for lifting said presser-foot after the unlocking of said device.

In testimony whereof I affix my signature in presence of two witnesses.

AUGUST R. SCHOENKY.
